[57] **CLAIM**

The ornamental design for a cubicle partition for cattle, similar article as shown.

DESCRIPTION

FIG. 1 is a perspective view of a cubicle partition for cattle showing my new design;

FIG. 2 is a left side elevational view thereof;

FIG. 3 is a top plan view thereof, the bottom being plain and unornamented;

FIG. 4 is a front elevational view thereof, the rear being a mirror image of the front view shown; and,

FIG. 5 is a right side elevational view thereof.

FIG.1
